UNITED STATES PATENT OFFICE

JOHN M. WHELTON, OF PEABODY, MASSACHUSETTS, ASSIGNOR TO UNITED SHOE MACHINERY CORPORATION, OF PATERSON, NEW JERSEY, A CORPORATION OF NEW JERSEY

LASTING AND SEWING MACHINE

Application filed December 3, 1929. Serial No. 411,368.

The present invention has relation to sewing machines in general, and relates particularly to sewing machines for use in the manufacture of stitch-down shoes and adapted to 5 perform the operation of uniting the outwardly-turned margin of the upper with the projecting edge of the sole, or insole, while these parts are assembled on a last.

The principal object of the invention is to 10 provide a machine adapted to draw the upper of an assembled stitch-down shoe down tightly over the last and to secure it to the sole by a line of stitches inserted and located so as to unite the upper permanently to the 15 sole in tightly-lasted relation. Another object of the invention is to enable this fastening of the upper to the sole by stitches to be accomplished upon a curved needle machine, so as to gain the advantages of this type of 20 sewing machine in ease of manipulating the shoe during the operation, and ability to place the stitches closely in the angle defined 25 between the side of the last and the projecting margin of the sole, without danger of the needle cutting or marring the upper material where it is supported by the bulging sides of the last.

To these ends, the invention comprises a 30 lasting and sewing machine having stitch-forming devices including a curved needle, and means for clamping the marginal portion of the upper against the outer portion of the projecting margin of the sole, and means acting while the upper is thus clamped to 35 wipe the material of the upper which bridges the angle between the last and the sole, down into this angle. This wiping action in bending the upper and tucking it into the angle draws the adjacent material of the upper 40 down tightly over the last since the edge-portion is held relatively tightly against movement through being clamped against the sole. While this relation is maintained, the curved needle of the stitch-forming devices 45 is passed obliquely through the sole as closely as possible at the exact edge of the sole-facing surface of the last, and through the upper as nearly as practicable on the line on which the upper is bent in being tucked into 50 the angle, so that at the completion of the

stitch following the withdrawal of the needle, the parts are permanently fixed in the desired lasted condition at this point. The clamping and wiping means are arranged to have a sidewise movement of their portions 55 engaging with the upper, so as to cooperate in feeding the work past the needle. Thereafter, while the needle is through the work, means act to lift the wiper and the clamping device clear of the work, and move them 60 sidewise back to their starting-point, after which the entire operation is repeated. This step-by-step simultaneous lasting and sewing action is continued about the circuit of the shoe, or about as much thereof as may be 65 desired, until the upper has been secured to the sole by a continuous seam forming a permanent and enduring union between these 70 two parts of the shoe, increasing the life of the shoe and imparting to it a neat and trim contour closely approaching that of a welt or turn shoe.

An illustrative embodiment of a preferred 75 form of the invention is shown in the accompanying drawings, in which:

Fig. 1 is a front elevation of a typical curved needle shoe sewing machine with the devices of the invention applied thereto, certain of the usual parts being omitted from the figure as unnecessary to an understanding of the invention;

Fig. 2 is a side view of the same, also with certain familiar parts omitted;

Fig. 3 is a sectional view on a larger scale 85 on line 3—3 of Fig. 1, of such parts as are closely connected with the invention, showing the action of the clamping and wiping members in lasting the shoe; and

Fig. 4 is a front view of the parts shown in 90 Fig. 3.

Having reference to the drawings, the principles of the invention are embodied, for purposes of illustration of its application, in a typical curved hooked needle shoe sewing machine of the Goodyear type, widely used to sew a chain stitch in uniting the upper, insole, and welt in making welt shoes, and in joining the upper and sole of turn shoes. Such a machine is shown and described in 95 U. S. Letters Patent No. 1,108,560, granted 100

on August 25, 1914 to Andrew Eppler, for a shoe sewing machine, to which patent reference may be had for a full and complete description of the construction and operation of such parts as are not shown or described hereinafter.

As heretofore, the machine is provided with the curved hooked needle 2 and the looper 4, which are operated in well-known manner through levers actuated by cams 6 on the cam-shaft 8 rotating in brackets 10 in connection with the frame of the machine.

In accordance with the invention, the machine is provided with a novel back-gage or work-rest 12, which engages the wearing or outer surface of the sole, being forked or slotted as at 14 to permit the passage of the needle 2. Its function is to support the shoe against the thrust of the clamping and wiping devices, and it is pivotally mounted by means of its sleeve 16 upon the stud 18 carried by the feed-slide 19, and on which the awl-segment 66 swings, so that it may be swung rearwardly and upwardly to permit the insertion and removal of the work without necessity for moving the clamping and wiping devices or the needle out of their timed relative positions. It is brought forward and locked in work-supporting position by a toggle-linkage comprising a link 22, pivoted at 24 to the back gage, and connected at 26 to one end of a lever 28 pivoted at 30 to a depending support 32 on the feed-slide. The rear end of this lever 28 is connected by a rod 34 to a spring-lifted treadle (not shown) which in its normal raised position holds the lever 28 in the position shown in Figures 2 and 3, with the center 26 below the line joining centers 24 and 30, and thus with the toggle locked to brace the back gage against the thrust of the clamping and wiping devices. Pressure of the operator's foot upon the treadle serves as is obvious to pull down the rod 34, breaking the toggle and swinging the back gage rearwardly and upwardly to permit insertion or removal of the work.

The device for clamping the overhanging edge-portion of the upper against the upper surface of the marginal portion of the sole comprises a member 36 which replaces the usual channel guide of the Goodyear machine, being attached to the channel-guide lever 38 by bolts 40 in the usual manner. This lever 38 as customary is mounted on the feed-slide to move laterally therewith, and to swing on the stud 42, being reciprocated with more amplitude than that given to a channel-guide through the proportioning of the parts. It is actuated through engagement of the notch 44 in its upper end by the tooth 46 on its cooperating cam lever. This cam-lever is of changed construction, and is made with a give-way joint at its pivotal point, so that the clamping member 36 will clamp the upper to the sole, and these two parts in turn against

the back gage, with sufficient pressure to attain the results desired regardless of the thickness of the stock, and so that continued movement thereafter of the cam lever derived from its cam 6 will not greatly increase 70 the pressure to the injury of the parts. Thus, the cam-lever is made in two parts, the driving tooth 46 being formed on the portion 48, while the cam-follower 50 is mounted on the rear-end of a portion 52, both portions having 75 a common pivot upon the stud 54. Upon the extension 56 of portion 52 forward of the stud 54 is pivotally mounted a pin 58 which slides freely through a swivelling eye 60 provided for it on the end of the portion 48. 80 About this pin is an expanding spiral spring 62 which exerts pressure in opposite directions against the eye 60 on portion 48 and against extension 56, tending to force them apart, this spreading action being limited by 85 a cotter-pin 63 through the end of the pin beyond the eye 60. With this arrangement, when the cam-follower 50 is moved radially inward of its cam 6 by the groove in the cam, the cam-lever will act as a unit to swing the 90 channel-guide lever 38 about its pivot 42, until the clamping member 36 presses the upper against the sole and the sole against the back-gage with a degree of pressure determined by the strength of spring 62. The degree of movement of portion 52 of the cam-lever is ample enough to insure tight gripping of the thinnest stock between the member 36 and the back-gage, and with thicker stock the spring 62 compresses after the 100 clamping member has been brought up firmly against the work, so that no damage is done to the parts while the portion 52 is completing its throw.

The device for wiping the upper down into the angle between the sole and the last comprises a wiping foot 64 that is fixed upon the usual awl-segment 66 in place of the awl, the segment being modified only so much as is necessary to provide for rigidly attaching the 110 wiping foot thereto. For this purpose, the awl-segment is formed with a shoulder 68 to lie alongside the shank of the wiping foot 64, to prevent change of its angular relation with respect to the awl-segment through turning 115 about on its attaching bolt 70, and the bolt-hole formed for the bolt 70 in the segment is elongated in the direction of extent of the wiping foot, to provide adjustment of its time of arrival in contact with the upper. The wiper is timed to engage the upper just as or after the clamping member 36 has clamped the upper against the sole-margin, and the wiper continues its downward movement between the clamping member 36 and the last, as shown in Fig. 3, to fold and tuck the upper into the angle between the sole and the last, the fold being brought close to or even under the edge of the sole-facing surface of the last. The acting extremity of the wiper 120

is wedge-shaped to conform to this angle, and engages the upper over a moderate extent in advance of and in close proximity to the needle. With the margin of the upper clamped 5 to the sole and bridging the angle, the descent of the wiper draws from over the last the added upper material entering into the bend that is pressed into the angle by the wiper, and in this way the upper is drawn down into 10 tightly lasted relation step by step as the operation progresses around the periphery of the sole.

The means for actuating the awl-segment are provided with a give-way to permit the 15 tucking movement of the wiper to be stopped by the resistance of the work without damage thereto when the upper has been properly seated in the angle. Such means comprise the link 72 connecting the arm 74 on the awl- 20 segment with the lower end of a lever 76 carried by the feed-slide and having a socket at its upper end to receive the rod 78 projecting down from the rocking stud 80 mounted in a bearing in the feed-slide. This lever 76 25 is actuated through its connection at 82 with the cam-lever which in accordance with the present invention is made in two parts with a give-way acting in one direction at the pivot 84, as in the case of the cam-lever for 30 the clamping member 36. The part 86 of this cam-lever which bears the pin 82 has a portion 88 provided with a swivelling eye 90, and also has a lug 92 formed back of its pivot 84. The other part 94 which has the cam-follower 35 96 to engage a cam-groove in one of the cams has a portion 98 to which is pivoted a pin 100, extending through the eye 90, and also has a lug 102 back of the pivot 84 to engage the corresponding lug on part 86. An 40 expanding spiral spring 104 surrounds the pin 100 and acts to hold the two lugs in engagement with each other. When the rotation of the cam carries the follower 96 inwardly radially of the cam, the whole cam- 45 lever acts as a unit to cause the wiper to press the upper into the angle. When the resistance of the work to further entry of the wiper increases past the degree determined by the strength of the spring 104 chosen, the 50 wiper and the part 86 remain at rest while the other part 94 completes the throw given it by its cam-groove, purposely liberal to accommodate the thinnest stock apt to be operated on by the machine. In this continued 55 travel of part 94, the lugs separate and the spring 104 is compressed, as is obvious. The re-engagement of the lugs upon reverse movement of part 94 insures positive retraction of the wiper out of engagement with the work during the reverse movement of the feed-slide after feeding, while the needle is through the work and holding the same.

The needle 2 is mounted and actuated in customary manner, being timed to enter the 60 wearing surface of the sole and emerge from

the upper while the latter is held tucked into the angle by the wiper, with the clamping member still clamping the upper against the sole and the sole against the back-gage. Arranged to pass close to the side of the wiper 70 as the latter comes to rest after its feeding movement, and in line with the wedge-shaped laterally-extending working edge thereof, the needle emerges exactly in the angle between the last and the sole, and in the corresponding angle formed in the upper by the wiper. In its retraction the needle draws tight the thread forming a stitch permanently uniting the parts in the lasted relation established by the cooperation of the wiper and clamping member. As the operation is repeated and the drawing-down and stitching proceed around the circuit of the last, the upper is progressively and evenly lasted 75 all around and united to the sole by a continuous seam sharply defining the outlines of the upper as determined by the last. This seam is well in under the edge of the last in a position least likely to be struck and cut by a needle in a subsequent outsole-stitching 80 or welt-applying operation, and being non-metallic in nature offers no risk of deflecting such needle with resultant damage to the work or the mechanism.

The nature and scope of the invention having been indicated, and the construction embodying the invention having been specifically described, what is claimed is:—

1. A lasting and sewing machine for stitchdown shoes having, in combination, stitch forming devices including a curved hooked needle, means for clamping the upper to the marginal portion of the sole, and a wiper acting to press the upper into the angle between the sole and the last while thus 100 clamped.

2. A lasting and sewing machine for stitchdown shoes having, in combination, stitch forming devices including a curved hooked needle, a clamping foot adapted to 105 clamp the upper against the marginal portion of the sole and to move laterally to feed the work, and means for pressing the upper into the angle between the sole and the last while thus clamped.

3. A lasting and sewing machine for stitchdown shoes having, in combination, stitch forming devices including a curved hooked needle, a clamping foot adapted to 110 clamp the upper against the marginal portion of the sole and to move laterally to feed the work, and a wiper moving in a curved path and adapted to press the upper into the angle between the sole and the last while thus clamped.

4. A lasting and sewing machine for stitchdown shoes having, in combination, stitch forming devices including a curved hooked needle, a clamping foot moving in 115 a curved path to clamp the upper against the 120

marginal portion of the sole, and means for pressing the upper into the angle between the sole and the last while thus clamped.

5. A lasting and sewing machine for stitchdown shoes having, in combination, stitch-forming devices including a curved hooked needle, a clamping foot moving in a curved path to clamp the upper against the marginal portion of the sole, and a wiper moving in a curved path and adapted to press the upper into the angle between the sole and the last while thus clamped.

6. A lasting and sewing machine for stitchdown shoes having, in combination, stitch-forming devices including a curved hooked needle, a clamping foot moving in a curved path to clamp the upper against the marginal portion of the sole and moving laterally to feed the work, and means for pressing the upper into the angle between the sole and the last while thus clamped.

7. A lasting and sewing machine for stitchdown shoes having, in combination, stitch-forming devices including a curved hooked needle, a clamping foot moving in a curved path to clamp the upper against the marginal portion of the sole and moving laterally to feed the work, and a wiper moving in a curved path and adapted to press the upper into the angle between the sole and the last while thus clamped.

8. A lasting and sewing machine for stitchdown shoes having, in combination, means for clamping the upper to the marginal portion of the sole, means for pressing the upper into the angle between the sole and the last, a back rest movable into position to support the shoe against the thrust of such clamping and pressing means, and out of position to permit entry and removal of the work, and stitch-forming devices uniting the parts of the shoe in the relation established by the clamping, pressing, and supporting means.

45 9. A lasting and sewing machine for stitchdown shoes having, in combination, stitch-forming devices and means for clamping the upper against the marginal portion of the sole and, while thus clamped, pressing the upper into the angle between the sole and the last, the clamping and pressing means cooperating to feed the work.

10. A lasting and sewing machine for stitchdown shoes having, in combination, 55 stitch-forming devices including a needle, lasting means including a member clamping the upper against the marginal portion of the sole and a member pressing the upper into the angle between the sole and the last while thus clamped, and a work-table adapted to be moved from its operative position to permit insertion and removal of the work while the devices referred to remain in their working relation to each other.

65 11. A lasting and sewing machine for

stitchdown shoes having, in combination, stitch-forming devices, lasting devices for pulling the upper down over the last while the stitch-forming devices are uniting it with the sole, a back-rest supporting the work against the thrust of the lasting devices, and toggle linkage adapted to be manipulated by the operator to move the back-rest into and out of its working position.

12. A lasting and sewing machine for 75 stitchdown shoes having, in combination, a work support engaging the outer surface of the sole, a clamping foot to clamp the upper to the marginal portion of the sole, means for pressing the upper into the angle between 80 the sole and the last, and stitch-forming devices uniting the parts in the relation established by the clamping, pressing, and supporting means including a curved hooked needle entering the work from the outer surface side and emerging at the angle formed 85 in the upper.

13. A lasting and sewing machine for 90 stitchdown shoes having, in combination, a work support engaging the outer surface of a sole assembled with an upper upon a last, means to clamp the upper to the marginal portion of the sole projecting beyond the last, and to press the upper into the angle between the sole and the last, and stitch-forming 95 devices uniting the upper and the sole in the relation thus established including a curved hooked needle entering the work from the outer surface and forming a seam in the angle.

100 In testimony whereof I have signed my name to this specification.
